UNITED STATES PATENT OFFICE.

WILLIAM J. WOODS, OF CORNING, NEW YORK, ASSIGNOR TO CORNING GLASS WORKS,
OF CORNING, NEW YORK, A CORPORATION OF NEW YORK.

PROCESS AND APPARATUS FOR MANUFACTURE OF BLOWN ARTICLES.

Application filed January 26, 1923. Serial No. 615,111.

To all whom it may concern:

Be it known that I, WILLIAM J. Woods, a citizen of the United States of America, residing at Corning, in the county of Steuben and State of New York, have invented new and useful Improvements in Processes and Apparatus for Manufacture of Blown Articles, of which the following is a specification.

For the purpose of convenience, this invention will be described as used in connection with and in carrying out the apparatus and method disclosed in U. S. Letters Patent 1,260,637, granted to the Empire Machine Company as the assignee of R. W. Canfield, although it will be understood, as herein-after pointed out, that this invention is capable of embodiment in other apparatus than that shown and claimed in the patent, and in carrying out methods other than those of the patent.

The machine described in the aforesaid patent is one especially adapted for the manufacture of electric lamp bulbs by a process involving the blowing of the bulb from a pressed blank after such blank has been elongated. It has been found, in practice, that under certain glass and blowing conditions, the walls of the neck of the bulbs, produced with the apparatus shown in that patent, are too thin, this resulting from the fact that the part of the blank which is to form the neck is unduly elongated in respect to the elongation of other portions of the blank. To remedy this my invention contemplates corrugating that part of the pressing surface of the pressing plunger which forms that portion of the skin of the blank, which, due to subsequent operations, will form the surface of the neck of the bulb, whereby the surface area of the blank at such point is increased without substantial change in the cross-sectional area of the blank at such point. This increase of surface area results in an increase in the thickness of the skin at such portion, due to the localized increase in the heat loss from the blank, either to the plunger in the pressing, or to the atmosphere, so that the elongation of the corrugated skin of the blank, and of the glass adjacent to such skin, is reduced.

Referring to the accompanying drawings,

in which corresponding parts are designated by corresponding marks of reference:—

Figure 1 is a section through a mold plunger embodying my invention;

Fig. 2 is a transverse section on the line X—X thereof, and

Figs. 3, 4, 5 and 6 represent successive steps in the formation of a bulb according to the method of this application.

The pressing plunger 1 is similar to the pressing plunger (designated by 81) of the aforesaid patent, except that the central cup-shaped recess therein is corrugated on its inner surface around the lower edge thereof, forming a series of serrations 2. It will be understood that these serrations, (for the purpose had in mind, namely, of increasing the surface area of the pressed blank without material change in cross-sectional area thereof) are rather numerous, close together, and shallow. In practice, I have employed about sixteen of these serrations to the inch, each serration having at its highest part the height of about one thirty-second of an inch.

In Figures 3 to 6, in which I have represented a method of forming a blown article by the use of my improved glass pressing part, and by present method, the plunger 1 is shown as having entered a suitable glass receiver 3 (corresponding to the receiver 10 of the aforesaid patent), the lower end of such receiver being closed by a glass-carrying spindle 4 such as described in the aforesaid patent. As shown, this spindle includes a dome-shaped head 6 (corresponding to the head 94 of the aforesaid patent). The pressing operation represented as being performed in Figure 3 is identical with that represented as being performed in Figure 27 of the aforesaid patent, except for the presence of the internal corrugations in the plunger 1. The blank having been thus formed, the plunger and glass-receiver are lifted off the end of the spindle, and the dome-shaped head 6 in the spindle is lowered, leaving the blank in the form of a meniscus support on the upper end of the spindle, as shown in Figure 4.

As described in the patent, the spindle is then inverted and puffed air is admitted into the interior of the blank to partly swell, and to aid in elongating the same, so that

the blank assumes the condition shown in Figure 5, which corresponds to Figure 27^h of the aforesaid patent. The blank has reached this stage by a stretching of its skin, and a flow of glass, the stretch for each portion of the surface, and the flow of glass at any point in the blank being effected by the temperature of the skin, and the temperature of the glass at such point. Due to the presence of the serrations on what is now the upper end of the blank, as is represented at 7, the flow of glass immediately adjacent to the serrated skin so formed will have been less than where the skin is smooth as in the aforesaid patent, leaving therefore, a thicker wall at this point. The bulb is now blown, as shown in Figure 6, with the result that the neck, the surface of which is formed by the serrated skin of the blank, will be thicker than would otherwise be the case.

The blowing operation in the mold 8 (which corresponds to the mold 52 of Figure 27 of the aforesaid patent) will entirely, or substantially, eliminate all traces of the corrugations or serrations produced on the original blank.

It will be noted that while I have disclosed my invention as applied to the manufacture of electric lamp bulbs, by the process indicated in the aforesaid patent, the invention is generally applicable to other cases in which a fresh blank is to be

elongated prior to blowing, and that in every such case, the location of the corrugations or serrations to be produced upon the press blank will be such as to locally cool that part of the surface of the blank which will be the surface of the portion of the wall of the finished article which it is desired to thicken.

Having thus described my invention what I claim as new, and desire to secure by Letters Patent is:—

1. A pressing plunger for forming glass blanks from which electrical lamp bulbs are to be blown, having an internal cup-shaped cavity, the surface of which, at points forming the surface of the blank which are subsequently to form the surface of the neck of the bulb is serrated.

2. The hereinbefore described method of blown articles from pressed blanks, and of locally controlling the attenuation of the thickness of a wall thereof during elongation, which consists in pressing a glass blank with serrations on that part of the surface thereof which will form, in the subsequent operation, the surface of the wall whose thickness is to be controlled, elongating the blank as controlled by such serrations, and blowing the blank to shape.

In testimony whereof, I hereunto affix my signature.

WILLIAM J. WOODS.
